UNITED STATES PATENT OFFICE.

EDWARD B. CRAFT, OF HACKENSACK, AND EDWIN H. COLPITTS, OF EAST ORANGE,
NEW JERSEY, ASSIGNEES TO WESTERN ELECTRIC COMPANY, INCORPORATED, OF
NEW YORK, N. Y., A CORPORATION OF NEW YORK.

METHOD OF AND APPARATUS FOR RECORDING SOUND.

Application filed November 28, 1919. Serial No. 341,156.

To all whom it may concern:

Be it known that we, EDWARD B. CRAFT, a citizen of the United States, and EDWIN H. COLPITTS, a subject of the King of Great Britain, residing at Hackensack, in the county of Bergen and State of New Jersey, and at East Orange, in the county of Essex and State of New Jersey, respectively, have invented certain new and useful Improvements in Methods of and Apparatus for Recording Sound, of which the following is a full, clear, concise, and exact description.

The invention relates to a method of and apparatus for recording sound and more particularly to sounds produced by the human voice and various musical instruments. The invention has for its object the elimination of certain difficulties heretofore encountered in sound recording.

In making records for reproduction in the well known types of sound reproducing machines, it has been necessary to take great precautions, particularly with respect to the relative location of the artist and the recording mechanism, and to employ artists who are specially trained in record making in order to obtain a record which will reproduce sound with any degree of faithfulness. Thus it has been common for the artist in the case of a voice record to sing or talk into a horn or mouthpiece and to vary the separation of artist and horn to obtain the desired tonal effects. In the case of instrumental music or in the case of duets or an ensemble of singers, great care has been necessary in grouping the singers or artists relative to the recording point in order to obtain the desired result. In view of the difficulty of training artists and also in view of the difficulty of grouping a large number of instruments for efficient recording, it has been proposed to intercept or pick up the sound waves at a plurality of points and conduct them either acoustically or electrically to a common recording point. Schemes of this sort, however, have not been entirely successful, for the reason that with a plurality of sound receivers or interceptors regardless of the care which may be exercised, the sound wave energy reaches the various receivers at different times, and consequently when the wave energy is transmitted to the recording point, that inter-

cepted by the various sound receivers are not in phase, which causes a disagreeable effect in the record which reproduces as an effect somewhat similar to an echo. In fact, this particular defect is often referred to as the echo effect and is caused by a difference in phase of effects produced by the same sound wave on the same record. When a large number of instruments are used for recording or where there is a soloist and an accompanist, it is of advantage to place the soloist and accompanist at different points in a room or auditorium and to control the relative tonal values of the soloist and the accompanist or, in the case of an orchestra, of the various instruments. This may be done as indicated in a copending application, of Harry B. Weir, Ser. No. 317,410, filed Aug. 14, 1919, by placing the performer and accompanist or various instruments each in individual soundproof compartments provided with sound receivers and conducting the sound from the compartments to a common recording point. While this scheme permits the adjustment of the relative tonal values, it involves very accurate time keeping between the artists in order to avoid the so-called echo effect since neither artist hears the effect produced by the other.

In accordance with the present invention, however, the artist or group of artists, may enter a room in which there is disposed at a plurality of different points a number of sound receivers, and the performance may take place identically as though the performers were appearing before an audience without regard to any special procedure occasioned by the making of the record. Since all of the sound receivers will be effected by all of the instruments and as no special precaution is taken to place the instrument or the soloist an equal distance from the receiving points, the invention provides for operating upon the wave energy between the point of interception or reception and the recording point to compensate for differences in phase or differences in time of arrival of the particular sound wave energy at the various receiving points. Although this compensation may be accomplished acoustically by varying the length of air path between the receiving and recording points, it can be more conveniently done by

converting the wave energy into electrical waves in electrical circuits and operating upon the electrical waves to bring them into phase in a common circuit where they may be combined to cause the operation of an electrically controlled record cutting stylus.

The present invention also contemplates including in the common portion or combining portion of the path between the 10 various receivers and the recording point means whereby a conductor or other operator may listen to or otherwise observe the combined effect and may make such changes as are necessary in the relative compensation 15 in the various individual paths from the receiver to the common point, to obtain the desired result.

These and other features of the invention will more clearly appear from the following 20 description and the accompanying drawing, in which the figure shows diagrammatically a recording system forming one embodiment of the invention. That part of the apparatus to the left of the dotted line on the 25 drawing may be located in an ordinary room or in an auditorium. The part to the right of the dotted line will ordinarily be grouped at some convenient point near the recording point so as to be under the control 30 of a single operator.

There is provided in the room or auditorium a plurality of sound receivers or detectors indicated at 1, 2 and 3. These may be spaced at various points about the room 35 or, in the case of an auditorium, they may be spaced at various points in the auditorium. Preferably they are located so that they will intercept the sound waves with efficiency regardless of the particular position 40 in which the artist or artist's instrument may face. Although only three of these sound receivers are shown, it will be understood that ordinarily a greater number will be used as may be determined by the size 45 of the room or auditorium. These sound receivers may be of any well known type in which the motion of a diaphragm or other sound responsive body is converted into variations of an electrical circuit. The type 50 which it is preferred to use because of the high quality of its production, is that disclosed in an application of I. B. Crandall, filed December 24, 1917, Serial No. 208,661 issued as Patent 1,456,538. Each sound receiver is connected in circuit with a source 55 of electrical potential indicated at 4, 5 and 6 respectively. The circuit including these sources of potential is connected by means of transformers or the ordinary telephone 60 repeating coils indicated at 7, 8 and 9 respectively, to a local circuit including in series inductances 10, 11 and 12 and capacities 13, 14 and 15 respectively. This local circuit when the inductances and capacities are properly selected functions as

an electrical wave filter in the manner described in a patent granted to G. A. Campbell, No. 1,227,113, on May 22, 1917. These filters may be arranged to pass only electrical waves of a frequency within the range 70 that it is desired to record so that noises due to movements of the performer or apparatus in the room, which are generally of very low frequency, may be eliminated. It is also possible to eliminate by this means certain 75 tones produced by resonance of various parts of the apparatus or musical instruments when subjected to vibrations in the neighborhood of their natural frequency. The filter circuits are inductively connected to transmission lines 16, 17 and 18 by repeating coils 19, 20 and 21. Each transmission circuit includes a thermionic amplifier 22, 23 and 24, which contains the usual heated filament 25, modifying or control electrode 26 and plate electrode 27. In order to vary the amplification produced by the amplifiers, there is provided a potentiometer 28 by means of which the energy impressed 80 on the input circuit of amplifier 22 may be regulated. The output circuit of the device includes a source of potential 29, a retard coil 30 and a condenser 31, the purpose of 85 which is well known in the art and need not be described here. 90

The output circuit of each amplifier is connected by means of transformer 32, 33 and 34 with adjustable artificial lines 35, 36 and 37, which are in turn inductively connected by means of transformers 38, 39 and 40 with a common circuit including an electromagnet 41 which operates a stylus 42 to cut a record face on the record surface 43. The artificial lines are of well known construction which have previously been used, 100 particularly in the telephone art, for the purpose of simulating a length of telephone transmission line. They are adjustable so that the length of line simulated may be varied at will. It is well known that an electrical wave in passing over a transmission line is retarded by an amount which is a function either of the actual or simulated length of the line. It is desirable 105 where tones other than pure tones are transmitted over a transmission line that the retardation of such tone, or the electrical impulse into which it has been converted be proportional to the frequencies making up the tone or impulse. An adjustable artificial line suitable for this purpose is disclosed 110 in an application to F. A. Hubbard, filed September 4, 1919, Serial No. 321,512. The effect, therefore, of adjusting the artificial line is to retard the electrical impulses or waves passing thereover to a greater or less degree. Also connected in the output 115 circuits of the amplifier are repeating coils 44, 45 and 46 with any one of which the telephone receiver 47 may be associated by 120 125 130

means of the switch 48. The receiver 47 may also be associated with a transformer 49 coupling the common recording circuit with the receiver by means of the switch 48.

- 5 The operation of making a record may now be described. The artist or artists merely enter the room or auditorium in which the sound receivers 1, 2 and 3 are located and without regard to the recording 10 apparatus, proceed with their performance. Sounds produced by an instrument or by the voice, say at a point marked A on the drawing, will reach the receiver 1 before reaching the receiver 2 and will reach receiver 3 after reaching receiver 2. Thus the 15 electrical impulses will be generated by the receiver 1 before a corresponding impulse is generated by the receivers 2 and 3. These impulses pass through the filters 10, 11 and 20 12 where undesirable frequencies are eliminated, and thence by the transmission lines 16, 17 and 18 through the amplifiers 22, 23 and 24 to the artificial lines 35, 36 and 37 respectively. It will be noted, however, that 25 the artificial line 35 is adjusted to include a larger number of sections of artificial line than the lines 36 and 37 and consequently retards the wave transmitted through it to a greater degree than the corresponding 30 waves transmitted over lines 36 and 37. Of course, this relative adjustment will depend upon the position of the performer or performers relative to the position of the various sound receivers and will ordinarily be 35 made by a conductor or operator who, by means of the switch 48, can connect his telephone 47 to the common circuit and readily determine by the effect heard in the common circuit whether the various artificial lines 40 have received the proper adjustment to bring the energy transmitted over the associated transmission lines into exact phase coincidence. The operator may also listen in on any of the individual circuits to make any 45 adjustment of the amplification which he may consider necessary.

It is therefore apparent that regardless of the relative position of the sound receivers and of the performer or performers or of 50 the movements of the performers which might alter such relative position, the differences in time of arrival of the same sound impulse at the intercepted or receiving point may be accurately compensated for, and 55 brought into phase coincidence at the recording point with the very much to be desired result of a natural and faithful record without requiring any restriction or special training upon part of the performers.

- 60 In the embodiment of the invention disclosed, which is the most efficient embodiment of which the inventors are aware, the sound wave energy is transmitted from the intercepting or receiving points to the recording point in the form of electrical waves,

but it is obvious that wave energy might also be transmitted from the intercepting to the recording point in other forms without departing from the spirit of the invention. For example, the wave energy might be 70 transmitted from the intercepting to the recording point, mechanically, instead of electrically, by means of a column of air as in the common speaking tube or stethoscope, or by means of a mechanical connection or 75 wire as in the mechanical telephone. In either case, it will be possible to alter the effective length of the conducting paths, and consequently to compensate for differences 80 in time of arrival of the wave energy at the receiving or intercepting points. A compensating device suitable for adjusting the relative lengths of a plurality of sound conducting tubes is disclosed in an application of R. M. Allen and G. F. Atwood, filed June 85 24, 1919, Serial No. 306,408.

What is claimed is:

1. A method of recording sound which consists in intercepting sound waves at a plurality of separated points, converting 90 said sound waves into electrical energy at said points, conducting said energy to a common point at different rates of speed to compensate for the difference in time of arrival of the sound waves at the intercepting points, 95 combining the electrical energy from the different points, and recording the effect of the combined energy.

2. A method of recording sound which consists in intercepting sound waves at a 100 plurality of separated points, converting said sound waves into electrical energy at said points, conducting said energy to a common point, retarding the electrical energy 105 due to the earlier intercepted sound wave to bring it into phase coincidence with the electrical energy due to the later interception of the same sound wave, combining the combined electrical energy at a common point 110 and recording the effect of said combined energy.

3. A method of recording sound which consists in intercepting sound waves at a plurality of separated points, converting 115 said sound waves into electrical energy, compensating said electrical energy for differences in time of arrival of said sound waves at the intercepting points, combining the effects of said electrical energy, and recording the combined effects.

4. A method of recording sound which consists in intercepting sound waves at spaced points, converting said sound waves into electrical waves, operating upon the phase of the electrical waves to compensate 125 for differences in the time of arrival of the sound at the intercepting points, combining said compensated waves and utilizing the combined waves to control the making of a record.

5. A method of recording sound which consists in intercepting sound waves at a plurality of spaced points, converting said sound waves into electrical waves, collecting said electrical waves into a common circuit, converting said electrical waves into audible effects for purposes of observation, adjusting the relative phase of the individual electrical waves until the desired combined effect is secured, and recording the effect of said combined waves. 60
6. In combination, sound receivers including means for converting sound waves into electrical waves, a recording device, conducting paths each connecting a respective receiver with said recording device, and means comprising an artificial line included in at least one of said conducting paths to shift the phase of the electrical wave energy transmitted through one path with respect to that transmitted through another. 65
7. In combination, a device for converting sound waves into electrical impulses, an electromagnetic recording device, a transmission line connecting said converting device and recording device, and means comprising an artificial line for adjusting the effective electrical length of said transmission line. 70
8. In combination, a plurality of sound receivers, a sound recording device, conducting paths from said sound receivers to said sound recording device, and means for relatively adjusting the effective length of said conducting paths. 75
9. In combination, a plurality of spaced devices for converting sound waves into electrical waves, a corresponding plurality of transmission lines, a common circuit with which said transmission lines are coupled, a recording device in said common circuit, and artificial lines included in said transmission lines to adjust the phase of the waves transmitted thereover. 80
10. In combination, a plurality of spaced devices for converting sound waves into electrical waves, a corresponding plurality of transmission lines, a common circuit with which said transmission lines are coupled, a recording device included in said common circuit, and artificial lines to bring the electrical waves transmitted over said transmission lines into phase coincidence before they are impressed upon said common circuit. 85
11. A system for recording sound comprising a plurality of devices for intercepting sound waves at a plurality of spaced points, means for converting said sound waves into electrical impulses, means for conducting said electrical impulses to a common recording point, means for compensating for differences in time of interception of said sound waves at the intercepting points to bring said electrical impulses into phase coincidence at the common point, and means for combining and recording the effects of said electrical impulses. 90
12. In combination, a source of sound, a plurality of spaced sound receivers for converting the sounds from said source into electrical impulses, a transmission line for each of said sound receivers, means in each of said lines for varying the effective lengths thereof, a circuit common to said transmission lines and electrically coupled thereto, and a recording device in said common circuit. 95
13. In combination, a source of sound, a plurality of spaced sound receivers for converting sounds from said source into electrical impulses, a transmission line for each of said sound receivers, an adjustable, artificial line in each of said lines for varying the effective lengths thereof, a circuit common to said transmission lines and electrically coupled thereto, and a recording device in said common circuit. 80
- In witness whereof, we hereunto subscribe our names this 25th day of November, A. D. 1919. 90
- EDWARD B. CRAFT.
EDWIN H. COLPITTS.
